UNITED STATES PATENT OFFICE.

WILLIAM P. WITHEROW, OF PITTSBURGH, PENNSYLVANIA, ASSIGNOR TO WITHEROW STEEL COMPANY, OF NEVILLE ISLAND, PENNSYLVANIA, A CORPORATION OF PENNSYLVANIA.

METHOD OF DIE ROLLING.

No Drawing.

Application filed July 16, 1925. Serial No. 44,111.

This invention relates to die rolling, and is particularly valuable for producing die-rolled articles in large quantities.

One of the most expensive items of the commercial operation of a die-rolling establishment is the initial setting of the rolls in the mill and the adjustment thereof to secure the desired results. These operations require a very large amount of time before any commercial product can be secured from the mill. The adjustments required in commercial die rolling are far more delicate than those in ordinary rolling practice, for it will be appreciated that the upper and lower rolls must be adjusted relative to one another, the temperature conditions must be accurately secured and maintained, and a number of other factors enter in, so that when the initial setting is once secured and commercial articles are produced, it is highly desirable to maintain such setting and keep the mill running as long as possible so as to secure maximum tonnage.

The limiting factor heretofore has been the fact that the roll grooves soon become roughened to such an extent that the surface of the article is materially affected, and in fact, the dimensions of the article are frequently changed by this roughening of the roll matrix patterns. This roughening is most apparent in those portions of the article where the greatest reduction from the leader is accomplished or where the section is very narrow. The side portions of the roll grooves soon become roughened and they seem to grip the hot leader in such manner that it can not flow smoothly into the groove and fill out. Consequently, the articles produced are not up to dimension and they present a very rough surface.

Heretofore when this condition has obtained, it has been necessary to shut down the mill and change rolls, thus materially increasing the expense. I provide for polishing matrix portions of the rolls while they are in the mill and have found that after such polishing the run may be continued. In actual practice, it has been found that a pair of rolls which were effective for producing commercial articles for only two or three hours might, by polishing in place, at two or three hour intervals, be used for eight or ten hours without material reduction in the quality of the die-rolled product. The pol-

ishing operation is carried out with portable grinders or polishers and may be accomplished within a very short space of time. In fact, the rolls are still quite hot when the second stage of the run is commenced and little or no further adjustment of the mill is required.

The side portions of the roll matrix, particularly in those portions where heavy reductions occur, will be found to be the roughest, and they will cause the corresponding portions of the article to present a very roughened and cracked appearance. Furthermore, those portions of the article are not up to dimension, as the free flow of the metal in the matrix is apparently interfered with by the rough walls and uncommercial articles are accordingly produced. When this condition is observed in the rolled product, the mill is stopped and one or two workmen immediately start to polish the matrix portions of the rolls. The work may very readily be carried out by having one man on one side of the mill work on the upper roll and another man on the other side of the mill work on the lower roll. Portable grinders or polishers have been used with great success, and the work of polishing a groove may be carried out in a very few minutes.

The dimensions of the matrix are not materially altered by the polishing operation, and it may be repeated a number of times without such changes in dimensions as will cause the production of articles outside the dimensional tolerances usually given.

By my invention, the time required for changing rolls and adjusting the mill need be spent only at the beginning of a run and the polishing operation may be carried out from time to time as required, in order to keep the articles up to the required standards. The expense of rolling is materially reduced by this step, and a far greater proportion of the mill time may be devoted to actual production rather than to the time-consuming steps necessary in the preparation of the run.

While I have described the preferred manner of carrying out the invention, it will be understood that it is not so limited, as it may be otherwise practiced within the scope of the following claims.

I claim:

1. The method of die rolling, which in-

cludes passing leaders between die rolls having matrix portions which vary in cross-sectional size or shape around the periphery of the rolls to produce a plurality of articles which are of different cross section at different points, such articles all being of substantially a desired length, continuing such operation until the rolls become roughened at the matrix portions thereof, discontinuing the run, polishing the roughened portions to insure that articles subsequently produced from the same rolls will be of substantially the desired length and will not have their length affected by the roughness of the rolls, and then utilizing the rolls for the further production of such articles.

2. In the method of die rolling, the steps consisting in passing leaders between normally rotating die rolls having matrix portions which vary in cross-sectional size or shape to produce a plurality of articles which are of different cross-sectional size or shape at different points, continuing the operation until the rolls have become roughened at the matrix portions thereof, stopping the rotation of the rolls and polishing the roughened portions of the rolls by guiding a polishing tool over such roughened portions while the rolls are inoperative.

3. In the method of die rolling, the steps consisting in passing leaders between nor-

mally rotating die rolls having matrix portions which vary in cross-sectional size or shape to produce a plurality of articles which are of different cross-sectional size or shape at different points, continuing the operation until the rolls have become roughened at the matrix portions thereof, stopping the rotation of the rolls and polishing the roughened portions of the rolls by guiding a polishing tool over such roughened portions while leaving other portions on the peripheral surface of the rolls unpolished, said polishing step being carried out while the rolls are inoperative.

4. In the method of die rolling, the steps consisting in passing leaders between normally rotating die rolls having matrix portions which vary in cross-sectional size or shape to produce a plurality of articles which are of different cross-sectional size or shape at different points, continuing the operation until the rolls have become roughened at the matrix portions thereof, stopping the rotation of the rolls and polishing those matrix portions where the greatest reduction is effected by guiding a polishing tool over such portions while the rolls are inoperative.

In testimony whereof I have hereunto set my hand.

WILLIAM P. WITHEROW.
